UNITED STATES PATENT OFFICE.

FRANK H. MAURER, OF PHILADELPHIA, PENNSYLVANIA, ASSIGNOR TO
JOSEPH W. MAURER, WILLIAM H. MAURER, ALEXANDER C. MAURER,
AND FRANK H. MAURER, OF SAME PLACE.

DESIGN FOR FRINGE.

SPECIFICATION forming part of Design No. 28,824, dated June 7, 1898.

Application filed January 28, 1898. Serial No. 668,356. Term of patent 3½ years.

To all whom it may concern:

Be it known that I, FRANK H. MAURER, a citizen of the United States of America, residing in the city and county of Philadelphia, 5 in the State of Pennsylvania, have invented and produced a new and original Design for Fringe, of which the following is a specification, reference being had to the accompanying drawing, showing said fringe.

10 In the drawing, A indicates the border or body of the fringe, from the lower edge of which depends a series of rounded loops B B, &c., said loops being arranged, as shown, so that each loop is intersected, so to speak, by

15 two other similar loops.

C C, &c., are knots from which depend tas-

sel ends D D, &c., said knots being secured to the center of each loop B, as shown.

The leading material feature of my design consists in the rounded border loops and 20 knotted tassels depending therefrom, substantially as shown.

Having now described my invention, what I claim as new, and desire to secure by Letters Patent, is—

The design for a fringe as herein shown and described.

FRANK H. MAURER.
